US00D631145S

(12) **United States Design Patent**
Beland et al.

(10) **Patent No.:** US D631,145 S
(45) **Date of Patent:** ** Jan. 18, 2011

(54) **HUMIDIFIER HOUSING**

D322,122 S 12/1991 Guetersloth et al.

(75) Inventors: **Stephane Joseph Pierre Beland,**
St-Jean-sur-Richelieu (CA); **Evelyne**
Tremblay, Chambly (CA); **Vincent**
Boutin, Montreal (CA); **Xin Hua Cao,**
Tianjin (CN)

DESCRIPTION

U.S. PATENT DOCUMENTS

2,101,603 A 12/1937 Stimson
3,491,746 A 1/1970 Swimmer et al.
3,672,706 A 6/1972 Chilcoat
4,158,679 A 6/1979 Yeagle
D253,846 S * 1/1980 Morrow D23/357
D258,609 S * 3/1981 Vogt D23/364
D280,660 S 9/1985 Muchenberger
D281,271 S * 11/1985 Meyer et al. D23/365
4,564,746 A 1/1986 Morton et al.
D283,265 S * 4/1986 Preskey et al. D34/28
4,589,409 A 5/1986 Chatburn et al.
D320,072 S 9/1991 Youngeberg

FIG. 1 is an upper right perspective view of the humidifier housing;

FIG. 2 is an upper left perspective view of the humidifier housing;

FIG. 3 is a front elevation view of the humidifier housing;

FIG. 4 is a left side elevation view of the humidifier housing;

FIG. 5 is a right side elevation view of the humidifier housing;

FIG. 6 is a top plan view of the humidifier housing; and,

FIG. 7 is a bottom plan view of the humidifier housing.

The features shown in broken lines depict environmental subject matter only and form no part of the claimed design.
